UNITED STATES PATENT OFFICE.

HARRY P. PRATT, OF CHICAGO, AND LEON O. MCPHERSON, OF JEFFERSON,
COOK COUNTY, ILLINOIS.

TELEPHONE-TRANSMITTER.

SPECIFICATION forming part of Letters Patent No. 355,838, dated January 11, 1887.

Application filed June 30, 1885. Serial No. 170,253. (No model.)

To all whom it may concern:

Be it known that we, HARRY P. PRATT, of the city of Chicago, and LEON O. MCPHERSON, of the township of Jefferson, in the county of Cook and State of Illinois, have invented certain new and useful Improvements in Telephone-Transmitters, of which the following is a specification.

Our invention relates to that class of telephone-transmitters wherein a diaphragm imparts the varying movements of sound-waves of the voice to the contact-surfaces of opposing electrodes of an electric circuit, and by changing or shifting the contact of said electrodes actuates the circuit to reproduce sounds in a receiving-instrument.

It has been found necessary in instruments of this class to provide means for adjusting the initial static pressure upon the electrodes with great care, in order to secure proper reciprocal action between them under all conditions and reproduce in the receiving-instrument the sounds which fall upon the transmitting-instrument.

It is also important to provide means which will counteract or destroy vibrations extraneous to those produced by the action of the voice directed against the diaphragm, as well as to dampen and tone down harsh and concussive sounds directed upon the diaphragm. The vibrations of the walls of a building and variations in temperature affect such instruments and destroy their delicacy of adjustment.

The object of our present invention is to provide an instrument of simple construction which will in a great measure fulfill the requirements above stated, and which shall be susceptible of great range and delicacy of adjustment.

The improvement consists, primarily, in suspending in rear of the diaphragm a free lever of novel construction provided with a weight adjustable thereon, to exert the required initial static pressure upon the electrodes without offering obstruction to the free movement of the diaphragm and electrodes.

The improvement consists, secondly, in a free lever suspended in rear of the diaphragm to bear upon a resiliently-supported electrode arranged upon one side of said free lever and a weight adjustably secured upon the opposite

side of said lever to variably dampen the vibrations of the diaphragm.

The improvement consists, thirdly, in supporting one or both of the carbon electrodes in an elastic socket or upon an elastic bed, preferably of soft rubber, to afford a yielding contact for the electrodes.

In the accompanying drawings, Figure 1 is a view in elevation of the rear side of the cover of a telephone-transmitter fitted with our improvements; Fig. 2, a vertical section in the line *x x* of Fig. 1, showing a simple form of free lever and adjustable weight for supporting the electrode; Fig. 3, a similar view showing a strip of spring metal arranged between the diaphragm and free lever for suspending one of the electrodes upon a resilient support or holder; Fig. 4, a like representation of a further modification of the device, wherein compound free levers are employed and an elastic cushion is arranged between the levers; and Fig. 5, a sectional detail of the lower end of the free lever provided with an elastic socket for the electrodes, as will hereinafter appear.

The cover *A* of the telephone-box supports a diaphragm, *B*, in any well-known or preferred manner. In this instance a peripheral ring of rubber, *C*, is arranged between the rim of the diaphragm and the inner side of the box-cover, and the diaphragm is held in place opposite the aperture *a* in said cover by means of screws *b* and metal clips *b'*, provided with rubber pads *b''*, which bear upon the rim of the diaphragm.

The diaphragm is provided with an electrode, *F*, in this instance of platinum wire arranged centrally thereto, against which is supported a carbon electrode in the following manner: A bracket or pivot-post, *D*, is secured to the inner side of the box-cover above the diaphragm, and supports a free lever, *E*, pivoted thereto at its upper end, and suspended to extend radially to the central portion of the diaphragm. The lower end of the free lever *E* is enlarged and recessed to receive a carbon electrode, *F'*, and the upper end of said lever is formed with an elbow, *e*, through the outer end of which the pivot-pin *e'* passes.

As the free lever is suspended from a point outside of a line passing centrally and longitudinally through it, the lever would rest in its

normal position in a line out of a vertical plane, and the carbon electrode F' at the lower end of said lever would tend to swing away from the diaphragm-electrode F when not otherwise acted upon. The free lever E is provided with means for nicely balancing and regulating its normal pendulous position and for accurately regulating and adjusting the degree of pressure exerted by it upon the electrodes in the following manner:

An arm, E', is screwed into the free lever to project rearwardly therefrom, and is screw-threaded to receive a weight, G, made adjustable thereon. The weight G may be placed upon the inner end of the arm E' immediately beneath the pivot-pin, where its power upon the lever would not be exerted, or it may be placed upon the outer end of the lever, to exert a much more than counterbalancing effect upon the free lever. With this range of adjustment in either direction any varying condition or requirement of adjustment may be complied with.

Both of the electrodes may be of carbon, if preferred, and may be connected with the line-wires H H' in the usual way. One of the electrodes, F, may be connected to the diaphragm in any well-known manner, as shown in Figs. 2 and 4, or it may be suspended upon a strip of spring metal, I, secured at its upper end to a post, i, on the cover, and held at its lower end between the lips of a metal holder, I', screwed to the cover, as shown in Fig. 3, which will admit of the free resilient movement of the spring.

The electrode F will in the arrangement thus described partake of a secondary vibration from the diaphragm and be held to closely follow its movements by the pressure of the weight in one direction and the resilient action of the spring in the other direction. The line-wires H H' are connected in this instance, respectively, to the upper end of the electrode-holder I' and to the upper end of the free lever E. A very simple and highly-sensitive mode of applying a free lever with an adjustable weight and resilient electrode-holder is illustrated in Fig. 4, wherein two free levers, E² E³, are suspended from a post, D, to swing alongside of each other in rear of the diaphragm.

A soft-rubber button, K, is secured to one of the levers to bear against the other and afford an elastic bed or cushion between said levers, which will effectually absorb or dissipate any jarring vibrations which may be imparted to the levers and diaphragm.

The weight may be delicately adjusted upon the arm of the lever to compensate for the proper degree of resiliency required in the spring or cushion, and thus accurately counterbalance the forces operating upon each other to secure the most sensitive responses to the

vibrations of the diaphragm. When two levers are suspended to act one upon the other, as above described, the jarring vibrations incident to freely-suspended or pendulous bodies, derived from forces other than the voice acting upon the diaphragm, will serve to partially counteract each other, and thus relieve the electrodes of false pressures and influences.

The attrition or frictional contact of one electrode upon another, especially when their surfaces become corroded or roughened by particles scaled or deposited thereon by electrical action, causes rasping or grating vibrations, which materially affect the delicate action of a sensitive instrument. These vibrating movements are greatly lessened and the effective working of the instrument increased by means of the carbon-holder shown in Fig. 5, wherein the lower end of the free lever E is bored through to receive a metal cup-pin, L, secured thereon by a nut, L', and recessed in its enlarged or headed portion to receive the carbon.

A soft-rubber sleeve, L², formed with a flanged head, l, is secured around the pin L, and between it and the bore of the free lever, which provides an elastic seat or socket for the carbon-holder and permits the carbon electrode to adapt itself closely at all times to its opposing electrode and yield to any rubbing or frictional pressure exerted upon it.

In conclusion, it may be remarked that the electrodes herein referred to may be made of any substance, material, or composition of matter of suitable conductivity.

We claim as our invention and desire to secure by Letters Patent—

1. In a telephone-transmitter, the combination, with the diaphragm, of the electrodes, a spring-actuated or elastic electrode-holder, an adjustable depending lever pivoted at one end to a bracket on the casing, a screw-threaded rod connected to said lever below its pivotal point and extending outwardly in a plane at right angles thereto, and a weight adjustably mounted on said rod, whereby a compensating pressure against the resiliency of the electrode-holder may be given, substantially as described.

2. In a telephone-transmitter, a cushioned electrode-support consisting of a metallic pin having a cup formed on one end for holding the electrode, and a screw-thread on its other end engaged by a nut, and an elastic cushion surrounding said pin and resting under the cup-shaped portion thereof, substantially as described.
